(57) CLAIM

The ornamental design for a violin body, as shown and described.

DESCRIPTION

FIG. 1 is a right-side elevational view of a violin body of the present invention;

FIG. 2 is a front elevational view thereof;

FIG. 3 is a back elevational view thereof;

FIG. 4 is a left-side elevational view thereof;

FIG. 5 is a top plan view thereof; and,

FIG. 6 is a bottom plan view thereof.

The broken lines are illustrated to show the environment only and form no part of the claimed design.
